UNITED STATES PATENT OFFICE.

WILLIAM A. RIDDELL, OF FREDERICK, MARYLAND.

SEPARATING OR CLASSIFYING MACHINE.

Application filed March 9, 1926. Serial No. 93,514.

My invention relates broadly to separating or classifying machines and more particularly to a construction of separating or classifying machine having a plurality of sets of rollers adjustable in position for grading material to different required sizes.

One of the objects of my invention is to provide a construction of separating or classifying machine in which a plurality of longitudinally extending roller members are arranged in a supporting frame with means for varying the spacial relation of the roller members in both a lateral and vertical direction for selecting a required spacial relation for the passage of material of selected sizes therebetween.

Another object of my invention is to provide a separating or classifying machine including a plurality of longitudinally extending roller members in which roller members of different sizes are arranged in spaced parallel relationship with means for adjusting the spacial relationship of the rollers for determining the size of the material which is subjected to the classifying process.

Still another object of my invention is to provide a construction of separating or classifying machine having a frame with longitudinally extending rollers journaled therein, with means for adjusting alternate ones of said roller members vertically with respect to stationary roller members journaled in the frame.

A further object of my invention is to provide a separating or classifying machine having a plurality of super-imposed frame members in which longitudinally extending rollers are journaled, the frame members being arranged to be adjusted vertically with respect to each other for interposing alternate rollers between other rollers of the frame for varying the longitudinally extending gaps between the rollers and thus determining the size of the material which may be passed through the rollers and discharged at the end of the classifying machine.

My invention will be more fully understood from the specification hereinafter following by reference to the accompanying drawings, wherein:

Figure 1 is a plan view of the separating or classifying machine of my invention; Fig. 2 is a longitudinal cross-sectional view taken through the separating or classifying machine of Fig. 1 along line 2—2 thereof;

Fig. 3 is a lateral cross-sectional view along line 3—3 of Fig. 1; and Fig. 4 is a fragmentary view showing rollers of smaller diameter adjusted to a position between the rollers 60 of larger diameter for selectively regulating the spacial relation of the rollers and governing the size of the material which may be passed between the rollers.

Referring to the drawings in more detail, 65 the classifying machine consists of side frame members 1 secured by suitable means such as bolt members 4 to rear bearing carrier 2 and front bearing carrier 3. A laterally extending casing 5 is provided at one 70 end of the coal separating machine forming a dirt proof housing for the shaft 6 journaled in the frame of the coal separator. The shaft 6 has a drive pulley 7 thereon which is driven by means of belt 8. Gears 75 9 are journaled on the shaft 6 co-operating with sets of bevel gears 10 and 29. A plurality of rotatable shaft members 11 are journaled in bearings 12 and 13 mounted in the bearing carriers 2 and 3. The shaft 80 members 11 carry rollers 14 which extend along the bottom of the hopper forming a part of the separating machine. I arrange a plurality of smaller rollers 15 intermediate the larger rollers 14, the smaller rollers 15 being carried by shafts 24 which are journaled in bearings 22 and 23 mounted upon an independent frame. The independent frame consists of longitudinally extending side frames 19 connected in opposite ends 90 by laterally extending frame members 20. Upwardly protruding arms 18 are provided adjacent opposite corners of the independent frame structure and these cooperate with bolt members 16 through slots 17 in the side 95 frames 1 to enable the independent frame structure to be adjusted vertically with respect to the main frame structure 1—2—3. The laterally extending frame members 20 provide adjustable mounts 21 for the sets 100 of bearings 22 and 23 and enable the spacial relation of shaft members 24 to be selected and set to a desired position. The extremities of the shaft members 24 are connected through universal joints 25 and loose coupling 26 with stub shafts 27 journaled in bearings 28. The stub shafts carry the bevel gears 29 which mesh with the gears 9 on the shaft 6. A hopper is provided over the rollers as defined by side plates 31 and chute 110 30 for directing the material to be separated in a path of travel over the rollers. The in-

105

110

dependent frame structure consisting of longitudinally extending frames 19 and laterally positioned frames 20 carrying the adjustably positioned rollers 15 may be moved vertically for thrusting rollers 15 to a position between rollers 14 thereby varying the spacial relation between the rollers. The position of the sets of rollers 14 and 15 may be varied to change the spacial relation between the rollers to such an extent that the rollers may be aligned axially as represented in Fig. 4 or the rollers may be substantially separated by adjustment of their bearings, and a combination lateral and vertical adjustment thereby secured. The material to be separated is dumped upon the chute 30 and gravitates over the sets of rollers which are normally positioned in an inclined plane. Material of a predetermined size passes between the rollers, while material of larger size is discharged at the end of the separating apparatus.

I have found the apparatus of my invention particularly suitable in the separation of coal, but it will be understood that the machine may be used for various purposes and that no limitations upon the use of the invention are intended. It will also be understood that other modifications of the invention may be made without departing from the spirit of the claims appended here-to.

Having thus described my invention what I claim and desire to secure by Letters Patent of the United States is as follows:

1. In a separating or classifying machine, the combination of a plurality of sets of longitudinally extending rollers, separate sets of bearings for alternate rollers, and means for adjusting the position of said bearings laterally with respect to each other and independent means for elevating or lowering one set of rollers with respect to the other set of rollers.

2. In a separating or classifying machine, the combination of a plurality of longitudinally extending rollers of two different sizes, the rollers of one size being alternately positioned with respect to the rollers of the other size, and means for adjusting the relative lateral and vertical positions between said sets of rollers.

3. In a separating or classifying machine, the combination of a frame, a drive shaft journaled laterally with respect to said frame, a plurality of rollers journaled longitudinally in said frame and rotated by said drive shaft, each of said rollers being laterally adjustable in said frame, an auxiliary frame member adjustably positioned within said aforementioned frame member, a plurality of longitudinally extending rollers journaled in said auxiliary frame member, said plurality of rollers being arranged to be moved in a vertical plane to various po-

sitions intermediate said first mentioned rollers for selecting the spacial relation of said rollers.

4. A separating or classifying machine comprising in combination a frame structure, a plurality of longitudinally extending roller members rotatably mounted in said frame structure, an independent frame structure adjustably mounted in said first mentioned frame structure and carrying a plurality of roller members thereon, said roller members being spaced apart in positions between the positions occupied by the roller members journaled in said main frame structure, whereby the spacial relation between said rollers may be varied by adjusting said independent frame structure with respect to said main frame structure, each of said rollers being independently adjustable laterally of said frame structures.

5. In a separating or classifying machine, the combination of a main frame structure, a plurality of rollers journaled longitudinally in said main frame structure, an auxiliary frame structure adjustably mounted with respect to said main frame structure, and carrying a plurality of longitudinally journaled rollers arranged to be interposed between the rollers journaled in said main frame structure for varying the spacial relation between said rollers, a rotatable drive shaft, a direct connection interposed between said shaft and the rollers on said auxiliary main structure and flexible connections between said shaft and rollers on said auxiliary frame structure.

6. In a separating or classifying machine, the combination of a main frame structure, a plurality of rollers journaled longitudinally in said main frame structure, an auxiliary frame structure, a plurality of rollers journaled longitudinally in said auxiliary frame structure and in positions substantially parallel with the axes of said aforementioned rollers, means for adjusting said auxiliary frame structure in a vertical plane with respect to said main frame structure for varying the vertical spacial relation between said rollers and independent means for adjusting the lateral relation between said rollers.

7. In a separating or classifying machine, the combination of a main frame structure, a plurality of rollers journaled longitudinally in said main frame structure, an auxiliary frame structure, a plurality of longitudinally extending rollers journaled in said auxiliary frame structure and in positions alternating with the positions of the longitudinally extending rollers in said main frame structure, means for adjusting said auxiliary frame structure with respect to said main frame structure for varying the spacial relation between said rollers for determining the size of material capable of passing between said classifying machine.

and independent means for varying the lateral spacial relation between said rollers in selected positions.

8. In a separating or classifying machine, the combination of a main frame structure, a plurality of rollers journaled longitudinally in said main frame structure, an auxiliary frame structure, a plurality of roller members adjustably positioned in said auxiliary frame structure and variable in lateral spacial relation and each offset with respect to the rollers journaled in said main frame structure, and means for adjusting the position of said auxiliary frame structure with respect to said main frame structure in a vertical plane for varying the spacial relation between said rollers and determining the size of the material which may be passed between said rollers.

20 9. In a separating or classifying machine, the combination of a main frame structure,

a plurality of rollers journaled longitudinally in said main frame structure, an auxiliary frame structure, a plurality of rollers journaled longitudinally in said auxiliary frame structure in positions intermediate the rollers journaled in said main frame structure, a drive shaft carried by said main frame structure for imparting rotary movement to each of said rollers, flexible driving connections between said drive shaft and the rollers journaled in said auxiliary frame structure, whereby all of said rollers may be driven simultaneously, and means for adjusting said auxiliary frame structure with respect to said main frame structure for varying the spacial relation between said rollers for determining the size of material which may be passed between said rollers during the classifying process. 40

In testimony whereof I affix my signature.

WILLIAM A. RIDDELL.
